INVENTOR,
James P. Ratigan;
BY *F. Maynard*,
ATTORNEY.

Patented Jan. 11, 1927.

UNITED STATES PATENT OFFICE.

JAMES P. RATIGAN, OF LOS ANGELES, CALIFORNIA.

BEAM-HANGER CABLE EYE.

Application filed April 14, 1926. Serial No. 102,089.

This invention relates to heavy duty apparatus wherein it is desired to connect a steel rope or cable to various forms of equipment, such for instance as the connection of pump hanger cables to their rod grips.

It has long been the practice to utilize a bridle cable whose ends are inserted in a socket and held by Babbitt metal poured into the socket to fill the interstices to bind the cable end in the socket so that when the eye of the socket is slipped onto a pin on the rod grip the cable cannot pull out.

The custom is to send the sockets to the customer and he babbitts in the cable ends. It will be seen that this requires use of a fire somewhere around the site commonly at the derrick shop of an oil well where there is much inflammable material, and often there is natural gas leaking from the well.

The broad object of my present invention is to provide means which will eliminate both the babbitting in and the melting out of the cable ends and, so, materially reduce the hazard of fire from such a source of danger.

Another object is to provide a device which, while being effective to firmly connect the cable to a desired part, as a rod grip, will permit of ready release and reattachment, or replacement, of the cable as may be required for several purposes or reasons; as to change length or size of the cable.

Another object is to provide a device combining a two-part cable-eye including a clamp feature so operative, when set, that the cable-eye is bodily reversible, on a pin, side for side and effects a center line of pull axially of the cable and medial plane of the eye-ring-body.

A further object is to provide a device which will securely grip upon cables of different diameters; will provide clearance for the usual strand-wrapping which is used to prevent unstranding; will not sharply angle or pinch the cable extending from the fastening; and will so kink the cable tail as to provide a safety feature against slipping.

Other objects and advantages will be made manifest in the following specification of apparatus embodying the invention, it being understood that modifications, variations and adaptations may be resorted to within the spirit of the invention and its scope as here claimed.

Figure 1 is a perspective of the applied invention.

Figure 2 is a top plan of the device.

Figure 3 is a perspective of the clamp eye.

Figure 4 is a longitudinal section showing a cable in place.

Some types of polish rod grips are provided with laterally projecting pins onto which are slipped the eyes of elongated sockets (as in my Patent #1,482,148.)

In such sockets the ends of a beam hanger cable is usually held by a filling of Babbitt metal. The operations of embedding and melting out the soft metal are obvious and the necessary fire is a hazard to be assiduously avoided around oil and gas fields.

In my present invention I aim to provide a beam hanger, cable eye wholly devoid of the babbetting feature, and possessing numerous advantages over such forms of sockets and eyes, as will now appear.

The present cable eye includes a main body part 2 having an elongated concaved seat 3 the lower end of which is angularly deflected at 4 to throw a substantial bend or kink in the tail end of the applied wire rope when it is clinched in place under a gripping plate 10. One end of the body 2 is provided with a stout ring or eye part 5 the plane of which is slightly offset as to the general plane of the body 2 so as to bring the medial plane of the eye-part in alinement with the axis of the average cable C utilized in the device.

It is to be observed that the far ends of the plate and the body are provided with outturned lips 17 which permit the cable to take a gradual turn without a sharp pinching corner action, when the cable sways as to the clamping parts 2-10. The plate is

interchangeable and is reversible endwise for application to the rope, each end having a lip 17. The short plate 10 provides, with seat part 4, a mouth for the outwardly deflected cable tail C' which is usually wrapped at 18 to prevent unstranding. The

wrapping clears the mouth and is not gripped by the parts, whose seats, obviously, are less, each, than 180 degrees angular length, as to the rope center so as to reliably clinch on any proper size of rope (cable).

The applied cable is subjected to a four point centering grip effect for the full length of the seats 3-11.

Ease of attachment and detachment, and light weight are achieved advantages.

Since fire destruction of oil, well platforms, shop-houses and derricks is no infrequent event the danger of dropping the load of parts by melting of the usual babbitt socket of the cable is wholly eliminated by my present clamp and eye means.

In Figure 3 the movable clamp plate 10 is hinged at 10^a on one side of the body 2. One bolt 7 serves to grip the cable in the clamp parts.

What is claimed is:

1. In a beam hanger, a bridle cable gripping means including a body part having on its cable axis a pin receiving eye-part whose axis is transverse to the length of the body part, and means hinged on the body for detachably clamping a cable end along the said part, said means including a single effective setting bolt, the pivot axis of the hinge means being parallel to one side of the cable lying axially on the body part.
2. In a beam hanger, a bridle cable gripping means including a body part having a pin receiving eye-ring whose axis is transverse to the length of the body part, and means hinged on the body part for detachably clamping a cable end along the body part; said eye-ring being bodily offset as

to the plane of the body so as to bring the medial plane of the ring in line of the axis of the applied cable end said means including a pivot pin disposed on the body and parallel to the cable axis.

3. In a beam hanger, a cable gripping means including a body part having on its cable axis a pin receiving eye-ring whose axis is transverse to the length of the body part, said part having a concaved cable seat along one face, and a movable clamping plate having a complementary clamping seat to set against the cable in the body seat, and single bolt-clamp means for fastening the plate and said body onto the cable and an elongated hinge pin and journals therefor along one side of the body and the plate; the pin lying parallel to the cable seats.

4. In a beam hanger, a cable gripping device including a body part having an eye portion with the axis of the eye transverse to the length of the body portion, a clamping plate terminating short of the eye portion, and hingedly connected to one side of the body on an axis parallel to an applied cable said eye portion having its ring bodily offset into a position partly under the said plate so as to approximately align with a cable gripped in said parts.

JAMES P. RATIGAN.
